GERMANY.

RECEIVING DEVICE FOR SUBAQUEOUS SOUND-SIGNALS.

1,391,681.

Specification of Letters Patent. Patented Sept. 27, 1921.

Application filed July 10, 1914, Serial No. 850,185. Renewed January 9, 1919. Serial No. 270,441.

To all whom it may concern:

Be it known that we, WALTER HAHNEMANN and HEINRICH HECHT, subjects of the German Emperor, residing, respectively, at 5 Kitzberg, near Kiel, and Kiel, 65 Feldstrasse, in the Kingdom of Prussia, have invented certain new and useful Improvements in Receiving Devices for Subaqueous Sound Signals, of which the following is a specification.

This invention relates to a receiving device for subaqueous sound signals which is so arranged that the sound waves arriving from a distant point impinge upon a receiver that is placed in the exterior water; that is, the water outside of the signaling station or the water in which the ship containing the signaling station is floating. A known arrangement consists in mounting 10 microphones, that which act as receivers, in spherical vessels, and in arranging these vessels so that they hang over the side of the ship and are thus suspended in the water. This shape of vessel gives the greatest possible security against pressure; but it has a great drawback in that it gives rise to the formation of eddies during the motion 15 of the ship, thus creating disturbing noises or vibrations in the receiver. The idea underlying this design of vessel seems to have been that by surrounding the microphone with liquid on all sides disturbing noises would not be imparted to the microphone. But it must be observed that, since the 20 microphone requires to be fixed in position by some kind of structure, it is not possible to attain a really perfect isolation of the microphone. It will be seen, that any arrangement will be advantageous which constitutes a step toward the suppression of 25 disturbing vibrations or noises. In designing an arrangement of this kind due regard may also be had to the aforementioned endeavor to protect the device against the 30 pressure of the water.

The present invention consists of an arrangement which has these advantages; and the essential feature of which is that the receiver, *e. g.*, the microphone, is laterally inclosed in a protective envelop, the outer surfaces of which are so shaped as to offer the least possible amount of resistance to the water that washes past them. In addition to this measure it is, of course, necessary to mount the entire device in a suitable man-

ner; namely, in such manner that the horizontal longitudinal axis of the vessel or envelop containing the receiver will lie in a direction that is the same as or substantially parallel to the direction of the longitudinal 60 axis of the ship.

A further recognized fact underlying this invention is that this way of mounting the device will not be advantageous at all parts of the ship; and since receivers are often 65 fixed to the bow or stern of the ship, another way of mounting the device must be employed in such cases. This consists in fixing the horizontal longitudinal axis of the envelop in such position that it coincides 70 with the current lines of the water. By this means the occurrence of a pressure component that would be caused by water currents or current lines striking the envelop in a direction at an angle to the horizontal 75 longitudinal axis of the enveloping surfaces is avoided.

In other words the invention consists in providing a protective envelop for the sound receiver, which envelop is of substantially 80 or approximately stream-line form and arrangement.

The direction of flow of the water current lines approximately conforms to the contour of the ship's hull, so that if the receiver is mounted at the bow or stern the horizontal longitudinal axis of the body or envelop containing the receiver would preferably be arranged to lie at a suitable angle 85 to the longitudinal axis of the ship in order 90 to obtain the best results.

In accordance with the invention it will sometimes be found sufficient to provide surfaces at the side of the receiving device, that are parallel to the ship's hull, but it will generally be more advantageous (especially if the receiver is to be made protrudable through the ship's side) to provide surfaces that inclose the receiver at all sides and form a watertight envelop. These enveloping surfaces will be curved so as to embody 100 stream-line principles, as for example in the shape of flattened hemispheres, such as shown in Fig. 4, in order to make them offer the greatest possible resistance to the pressure of the water while also making them 105 easy to construct. The plain spherical shape of envelop was mentioned above, and its disadvantages were pointed out.

Figures 1 and 2 illustrate different forms 110

of the invention. The drawings are principally diagrammatic since the invention consists in the shape and arrangement of the device, and the details of the device itself 5 are known.

Fig. 3 illustrates more clearly and in perspective the enveloping surfaces of the receiving device of Fig. 1; while Fig. 4 shows the shape of the enveloping surfaces of the 10 device of Fig. 2.

Fig. 1 illustrates particularly how the receiver comprising a microphone M is fixed at the ship's side in the zone of the current lines about the bow of a ship S. The shape 15 of the current lines is, as indicated in the drawing, approximately that of the ship's sides. According to the invention the microphone is inclosed laterally by surfaces F forming a protective envelop for the microphone. These surfaces join at two ends and 20 are shaped as illustrated in Fig. 3. The microphone may be held in position by rubber cords. The horizontal longitudinal axis of the envelop lies in the direction of the 25 current lines, or forms a tangent with these lines at the point where the device is fixed.

It is assumed that the device is attached to the ship's side, as indicated in Fig. 2, by a rigid rope or the like which contains the 30 electrical conductors leading to the microphone. The vertical dimensions of the enveloping surfaces of the device shown in Figs. 1 and 3 is such that the water inclosed 35 between them is quite quiescent so that the microphone can be held by a comparatively slender and light fixture.

In the example described and shown in Figs. 1 and 3 the water is not kept out of the inclosed space. But in the example shown

in Figs. 2 and 4 the enveloping surfaces 40 completely surround the microphone. They consist of two curved plates which are tightly joined to each other and inclose a space that is filled with liquid in which the microphone is suspended. The envelop that 45 thus contains the microphone narrows down toward the front and rear so as to approximate stream-line form and offer the least possible resistance to the water.

We claim:

1. A submarine sound signaling plant in combination with a vessel, comprising a sound receiver surrounded by a protective envelop consisting of plates laterally inclosing said receiver and rigidly connected with 55 said vessel; said envelop being arranged in the passing water, and being of substantially stream-line form and arrangement to prevent the formation of eddies in the passing water.

2. A submarine sound signaling plant in 60 combination with a vessel, comprising a sound receiver surrounded by a protective envelop consisting of plates laterally inclosing said receiver, and means carrying said envelop rigidly connected with said vessel; said envelop being arranged in the passing water, and being of substantially 65 stream-line form and arrangement to prevent the formation of eddies in the passing water.

In testimony whereof we affix our signatures in presence of two witnesses.

WALTER HAHNEMANN.
DR. PHIL. HEINRICH HECHT.
